UNITED STATES PATENT OFFICE.

RICHARD A. LEADBETTER, OF DETROIT, MICHIGAN, ASSIGNOR TO THE FARRAND COMPANY, OF DETROIT, MICHIGAN, A CORPORATION OF MICHIGAN.

AUTOMATIC PLAYING MECHANISM FOR GRAND PIANOS.

1,108,997.

Specification of Letters Patent.

Patented Sept. 1, 1914.

Application filed July 16, 1912. Serial No. 709,685.

To all whom it may concern:

Be it known that I, RICHARD A. LEADBETTER, a citizen of the United States of America, residing at Detroit, in the county of Wayne and State of Michigan, have invented certain new and useful Improvements in Automatic Playing Mechanism for Grand Pianos, of which the following is a specification, reference being had therein to the accompanying drawings.

10 The invention relates to combined manually operable and automatic pianos and has particular reference to a construction for grand pianos.

15 The invention consists in the novel construction and arrangement of the automatic action in combination with the manually operable action, and further in various structural features as hereinafter set forth.

20 In the drawings: Figure 1 shows a portion of a grand piano in longitudinal section with my invention applied thereto. Fig. 2 is a cross section.

25 A is the case of a grand piano; B is the key bed; B' the key frame; C the key levers; and D the striking action. The key levers communicate movement to the striking action through the vertical rods E secured thereto, which at their upper end engage horizontal levers F; all the parts thus far described being of known construction.

30 It is one of the objects of the invention to arrange the automatic action so as not to require any radical change in the manually operable action or in the construction of the piano case. To this end the pneumatic action is arranged in front of the striking action at a point opposite the fulcrum of the key levers, in which position it will not 35 interfere with any of the mechanically operating parts of the instrument, or impair the tone quality.

35 The automatic action comprises a plurality of tiers of striking pneumatics G G', etc., preferably connected with a metallic action H; and I is a guide for a series of vertical rods corresponding in number to the keys of the piano. A portion of these rods J are connected to the pneumatics below the 40 guide I and extend upward, while additional rods L are arranged above the guide I and are provided with fingers M which project forward into the plane of the rods J but out of alinement therewith. The connection between the rods J and L and the 45 striker action is through the medium of

horizontally arranged levers N, which are fulcrumed at their rear ends to a bar O, and intermediate their ends are slotted for the passage of the rods E of the piano action. Upon these rods E are the buttons P, which are in the path of the levers N so that the operation of said levers through the medium of the rods from the pneumatics G G', etc., will impart an upward movement 60 to the rods E.

65 In the adjustment of a piano action it is seldom possible to adjust the mechanism for the various keys precisely the same. This necessitates provision for adjustment with 70 respect to the automatic action, and I have accomplished the desired result in a simple way by the following construction. Each of the levers N is provided at its free end with an adjustable button Q, preferably connect- 75 ed by a turn-screw R, and which is arranged in alinement with the rods J. There are also provided opposed stops S and T for limiting the movement of the levers N, which are adjustable through threaded 80 shanks U engaging supporting bars V. The button P upon the rod E is also adjustable, preferably by a threaded engagement with said rod. Thus to adjust the instrument the limits of movement of the lever N may be 85 determined by adjustment of the stops S and T, while the adjustment of the buttons Q and the adjustment of the screws R and the adjustment of the buttons P, will compensate for any variation in the adjustment 90 of the piano action. The action of a grand piano is all mounted upon the key frame such as B', and whenever necessary the whole structure is removable as a unit from the piano case. To permit of this disengagement of the action with my improved 95 construction, I have mounted portions of the pneumatic action also upon the key frame, while a detachable connection is provided with this pneumatic action, the bellows, and other parts that are stationary in 100 relation to the piano frame. As shown in Fig. 2 the pneumatic action H is mounted through the medium of uprights H' and H² at opposite ends thereof upon the key frame 105 B', and the shelf W which supports the tracker W' and motor W² is also supported at opposite ends upon the key frame. X is the bellows arranged below the key bed B and connected by a conduit X' beneath the 110 bed to an extension of said conduit X², passing through the bed and coupling to the

pneumatic action. This extension X^2 is to be made detachable from the conduit X' in any approved manner and when detached will permit the removal of the key frame with all portions of the mechanical and pneumatic action supported thereon. There is also provided a detachable conduit connection, not shown, similar to the conduit X' for operating the motor.

10. What I claim as my invention is:

1. In a grand piano, the combination with the piano action and manually operative key levers, of a pneumatic action arranged in front of the piano action, horizontally extending levers pivoted at their near ends, and adjustable pins carried by the free ends of the horizontal levers for engagement with the pneumatic action.

2. In a grand piano the combination with 20 a piano action and key levers having rods extending vertically therefrom, of a pneumatic action arranged in front of the piano action, and levers extending horizontally above the key levers, engaging at their free 25 ends with projections on the pneumatic action and intermediate their ends loosely engaging with the vertical rods of the key rods.

3. In a grand piano the combination with 30 the piano action, and key levers having vertical rods extending upward therefrom, of a pneumatic action arranged in front of said piano action and provided with a plurality of tiers of striking pneumatics, horizontal levers arranged above the key levers, fulcrumed at their rear ends, the forward ends of said levers being connected with said striking pneumatics, and loose engaging means between intermediate portions of 40 said levers and the vertical rods on said key levers.

4. In a grand piano the combination with 45 the piano action, and key levers having vertical rods extending upward thereon, of a pneumatic action arranged in front of said piano action, and horizontal levers arranged above said key levers, being fulcrumed at their rear ends and slotted intermediate their ends for the free passage of said vertical rods, adjustable engaging means between said rods and said levers, adjustable means between the free ends of said levers and the striking pneumatics, and an adjustable stop, for limiting the movement of 55 each lever.

5. In a grand piano the combination with a piano action, and key levers having vertically extending rods thereon, of a pneumatic action arranged in front of said piano 60 action, horizontally extending levers above the respective key levers, fulcrumed at their rear ends and slotted intermediate their ends for the free passage of said vertical

rods, adjustable buttons on said vertical rods against which said levers are positioned 65 to strike, and adjustable connection between the free ends of said levers and their respective pneumatics, and adjustable stops for limiting the movement of said levers.

6. In a grand piano the combination with 70 a piano action, and key levers having vertically extending rods thereon, of a pneumatic action, arranged in front of the piano action above the key levers, horizontal levers fulcrumed at their rear ends and at 75 their forward ends engaging the respective key actuating pneumatics, adjustable bearings on said vertical rods for loosely engaging the respective horizontal levers at points intermediate their ends, adjustable 80 stops for limiting the movement of the free end of each horizontal lever, and adjustable connection between the free end of said lever and its actuating pneumatic.

7. In a grand piano the combination with 85 a piano action, and key levers having a vertically extending rod connected thereto, of a pneumatic action, arranged in front of the piano action above said key levers and comprising a plurality of tiers of striking 90 pneumatics, operating fingers connected to the pneumatics in the several tiers, arranged in horizontal alignment with each other, horizontal levers for the respective key levers arranged thereabove, being fulcrumed 95 at their rear ends, their forward ends being in proximity to the respective actuating fingers and being intermediate their ends in proximity to said vertical rods, adjustable members on said rods for loosely engaging 100 said levers, adjustable connections between the free ends of said levers and said fingers, and stops for limiting the movement of said levers.

8. In a grand piano the combination with 105 the key bed and a key frame detachably supported thereon, of a pneumatic player action mounted upon said key frame and removable therewith.

9. In a grand piano the combination with 110 the key bed and a key frame detachably mounted on said bed, of a pneumatic player action mounted upon said key frame, a bellows and co-operating mechanism arranged beneath the key bed and a detachable conduit connecting said bellows with the pneumatic action and permitting when detached the removal of said action with the key frame.

In testimony whereof I affix my signature 120 in presence of two witnesses.

RICHARD A. LEADBETTER.
